VENDING MACHINE

Wallace V. Weirich, Chicago, Ill., assignor to
O. D. Jennings & Company, Chicago, Ill., a
Corporation of Illinois

Application July 9, 1932. Serial No. 621,556

7 Claims. (Cl. 194—1)

My invention relates to vending machines of the type which automatically dispense merchandise and coupons or tokens with each or certain sales in order to enhance sales by the machine.

5 In this type of machine it is, of course, necessary to refill the coupon or token reservoir which is necessarily within the cabinet and inaccessible from the exterior. Heretofore it has been necessary to open the locked cabinet surrounding the 10 machine to gain access to the mechanism and in some cases remove the mechanism from its closure or cabinet to refill the coupon reservoir.

This refilling is frequently done by persons unskilled and unfamiliar with vending machines. 15 This is particularly true where the machines are owned by one party and operated upon the premises of another who obtains a certain percentage of the operating proceeds of the machine, but has no further interest in the machine. In such 20 cases it is particularly desirable that the owner of the premises be able to refill the coupon reservoir without necessarily having access to the vending machine proper or coin reservoir. It is also desirable that some record be made of the 25 number of tokens placed in the token reservoir.

It is the purpose of this invention, therefore, to provide means in a vending machine of the above character whereby the coupon reservoir of the machine may be replenished without opening or in any way permitting access to the interior of the machine, and whereby the number of tokens placed in the reservoir can also be determined from the exterior of the machine.

In accordance with this invention I have provided 35 setting mechanism which, in effect, disassociates the vending mechanism from the coupon reservoir to permit filling of the token reservoir without operation of the vending mechanism and for automatically counting and registering 40 the coupons placed in the machine, the setting mechanism being operable from the exterior of the machine in such a manner as to eliminate the necessity of opening the machine and to eliminate all possibilities of disputes between the 45 proprietor of the premises in which the machine is located and the owner of the machine or any others interested therein.

Other novel features of construction and their 50 advantages will be apparent from the following description given in connection with the drawings in which:

Fig. 1 is a perspective of a complete electrically operated machine embodying the novel features of my invention,

55 Fig. 2 is an enlarged fragmentary side eleva-

tion of the setting mechanism embodying this invention,

Fig. 3 is a similar fragmentary or partial side elevation of a slightly modified form of my invention.

The invention is illustrated as being applied to an electrically operated machine housed in any suitable attractive cabinet 1, having a coin slot 2 and an operating electrical switch 3 in the top thereof. The illustrated machine merchandises four varieties of confections which may be seen through windows 4 and which may be selectively purchased by operating buttons 6, the confection being dispensed through an opening 7 through which coupons or tokens will also 70 be dispensed under certain predetermined conditions. The type of machine is well known and need not be described in greater detail.

Referring more particularly to Fig. 2, a portion of the base 8 and one end plate 9 of the dispensing mechanism is illustrated. In general, the machine is actuated by a coin controlled actuating member or arm 11 which carries a dog 12, pivoted thereto at 13, which engages a stationary dog 14 adjustably secured to an arm 16, rigidly 80 secured to the end of the vending machine actuating shaft 17. The foregoing mechanism is the usual construction in this type of machine, one example of which is shown in the Hassman Patent 988,570, issued April 14, 1911, and therefore need not be described in further detail.

To swing dog 12 in a counter-clockwise direction about its pivot to cause it to clear the stationary dog 14 when the actuating member is rotated, as indicated in dotted line, a cam lever 90 18 is pivoted about a screw 19 threaded into the end frame in position to engage dog 12. That is, lever 18 has a cam surface 21 which engages dog 12 when the lever is in its extreme counter-clockwise position and swings dog 12 in a counter-clockwise direction, causing it to clear fixed dog 14. Lever 18 is moved into operative or inoperative position by a slide 22 which has a depending finger 23 carrying a pin 24 which projects through the lower end of lever 18 to swing the 100 latter about its pivot 19. Slide 22 is retained against the end plate 9 by guide 26 secured to the end plate, and is further retained in its left position as viewed in Fig. 2 which is the inoperative position of cam lever 18, by a spring 27.

Slide 22 is, of course, provided upon its inner end with an arcuate slot 28 to permit passage of pivot 19 and is provided upon its outer end with an upstanding finger 29 which carries a pin 31 which is engaged by the bolt 32 of a lock 33 which 110

extends through the side wall of the cabinet as shown in Fig. 1 and by means of which slide 22 may be moved to throw cam lever 18 into inoperative position whenever desired without opening or entering the cabinet. Bolt 32 is held in either of its two extreme positions by an off-center spring 34. When lever 18 is moved into inoperative position by movement of lock 33 to clear dog 12 of fixed lever 14, the coin controlled actuating arm may be operated repeatedly at will without actuating the vending mechanism, and therefore coupons may be fed into the coin chute and will be delivered into the token reservoir 36 in the usual manner.

To count and register the coupons that are placed in the chute, a counter 37 is disposed within the cabinet adjacent the rear wall thereof, which wall is provided with an opening through which the dial of the counter may be observed. The counter is actuated by an arm 38 secured to the counter shaft to which is pivotally connected a link 39, (the center portion of which is broken away in Fig. 2) the lower end of which is pivotally connected to the rear end of a lever 41 pivoted intermediate its ends at 42 to the end frame of the machine. The opposite end of lever 41 is provided with an out turned flange or platform 43 which engages the lower end of dog 12 and, when permitted rises with the dog under action of leaf spring 44 to pull link 39 downwardly and actuate counter 37.

Intermediate pivot 42 and flange 43 lever 41 is provided with a shoulder 46 which engages pin 24, as shown in full lines in Fig. 2, and prevents lever 41 from rising with dog 12 when slide 22 and pin 24 are in left position. When slide 22 and pin 24 are moved out or to the right by action of lock bolt 32, pin 24 clears shoulder 46 as illustrated in dotted line position in Fig. 2 and permits lever 41 to rise. The counter does not indicate an actuation of the operating lever 11 when the vending machine is being normally used to dispense merchandise as in this condition the slide is to the left.

In Fig. 3 there is shown a slightly modified form of refilling setting mechanism and counter-actuating mechanism. In this form of my invention the refill setting slide is designated as 22^a. This slide is similar to slide 22 of the form of my invention shown in Fig. 2 with the exception that the pin 31, instead of engaging the lock bolt directly carries a rod 47 which extends through the rear wall of the cabinet and terminates in a knob 48. Within the interior of the cabinet rod 47 is provided with a slot in its side which is engaged by a bolt 49 of a lock 51 which extends through the rear wall of the cabinet instead of the side wall. In this form of my invention instead of the lock throwing the slide into inoperative position for refilling purposes, the knob 48 must be gripped by the operator to pull the slide to the right into inoperative position. In this position an exterior latch 52 may be pushed downward to engage the slot in rod 47 which then lies upon the exterior of the cabinet to hold the slide out.

The counter actuating mechanism is also slightly modified as can be seen from the drawings. In this form the arm 38 upon the counter shaft is connected by link 53 to one end of a pivoted lever 54 and the lower end of the lever terminates in a foot 56 which is engaged by a vertical bar 57 carried by cam lever 18 as shown in dotted lines in Fig. 3. Bar 57 is secured to lever 18 by a pair of rivets 58 which project through slots

in the bar. Bar 57 is thereby permitted to move upwardly and ride over the footed end 56 upon the downward stroke of the cam lever 18. When cam lever 18 and slide 22^a are in retracted position, bar 57 is inclined to the right so as to clear lever 54, as is shown in full line in Fig. 3. Therefore, in the normal operating position the counter is not actuated. When the machine is set for refilling however, bar 57 is moved to the left as shown in dotted lines in Fig. 3 and engages lever 54 to actuate counter 37.

The operation of either form of my invention is readily understood from the foregoing description and it can be readily appreciated that when it is desired to refill the coupon reservoir, slide 22 or 22^a is moved outwardly or rearwardly of the machine by either the lock tumbler or by grasping knob 48 to throw cam 21 to the right to move dog 12 about its pivot so as to clear fixed dog 14. The same motion also throws the counting mechanism into operation. After a sufficient number of tokens have been placed in the reservoir, the slide may be returned to normal or inoperative position and the number of tokens placed in the machine recorded from counter 37.

It will be apparent that either form of counting mechanism may be used with either form of setting mechanism, that is, the counter actuating mechanism of Fig. 3 may be used in place of that shown in Fig. 2 or vice versa, and that many other variations may be made in the details of construction without departing from the spirit and scope of this invention as defined in the appended claims.

I claim:

1. In a coin controlled vending machine including a cabinet having mechanism therein for dispensing merchandise and coupons, a reservoir for coupons, means for disengaging the dispensing mechanism while refilling the coupon reservoir, means extending through said cabinet to the exterior thereof for operating said disengaging means to set the machine to refilling position, a counter and means operable when the dispensing mechanism is disengaged for actuating the counter to record the coupons fed into the coupon reservoir, said latter means being inoperative when the dispensing means is engaged.

2. In a coin controlled vending machine including a cabinet having mechanism therein for dispensing merchandise and coupons, a reservoir for coupons, means for disengaging the dispensing mechanism while refilling the coupon reservoir, means extending through said cabinet to the exterior thereof for operating said disengaging means to set the machine to refilling position, a counter and means actuated by said disengaging means when the dispensing mechanism is disengaged for actuating the counter to record the coupons fed into the coupon reservoir, said latter means being inoperative when the dispensing means is engaged.

3. In a coin controlled vending machine including a cabinet having mechanism therein for dispensing merchandise and coupons including a coin controlled actuating member and a separate reservoir for coupons, means for disengaging the dispensing mechanism from operation by said member to permit independent operation of the latter to refill the coupon reservoir, means extending through the cabinet to the exterior thereof for operating said disengaging means, a counter and connections for operating said counter to record movements of said actuating

- member when operated independently of said dispensing mechanism.
4. In a coin controlled vending machine including a cabinet having mechanism therein for dispensing merchandise and coupons, comprising a coupon reservoir, a coin controlled actuating member, a pivoted dog carried thereby, a shaft for operating said dispensing mechanism and having a fixed dog thereon adapted to be engaged by said pivoted dog, a movable cam arranged to contact said pivoted dog when in one position to move the latter out of possible engagement with said fixed dog to disengage the dispensing mechanism from operation by said actuating member, means extending through the cabinet to the exterior of said cabinet for moving said cam, means for counting the movements of said actuating member when the dispensing mechanism is disengaged, said counting means being inoperable when the dispensing mechanism is set to be engaged by said pivot dog.
5. In a coin controlled vending machine including a cabinet having mechanism therein for dispensing merchandise and coupons, comprising a coupon reservoir, a coin controlled actuating member, a pivoted dog carried thereby, a shaft for operating said dispensing mechanism and having a fixed dog thereon adapted to be engaged by said pivoted dog, a movable cam arranged to contact said pivoted dog when in one position to move the latter out of possible engagement with said fixed dog to disengage the dispensing mechanism from operation by said actuating member, means extending through the cabinet to the exterior of said cabinet for moving said cam, means for counting the coupons placed in said reservoir when the dispensing mechanism is disengaged, said counting means being inoperable when the dispensing mechanism is operated by said pivoted dog.
6. In a coin controlled vending machine including a cabinet having mechanism therein for dispensing merchandise and coupons, comprising a coupon reservoir, a coin controlled actuating member, a pivoted dog carried thereby, a shaft for operating said dispensing mechanism and having a fixed dog thereon adapted to be engaged by said pivoted dog in normal operation of the machine, a pivoted cam arranged to contact said pivoted dog when in one position to move the latter out of possible engagement with said fixed dog to disengage the dispensing mechanism from operation by said actuating member, a slide engaging said cam for swinging the latter, and lock controlled means operable from the exterior of said cabinet and connected to said slide for operating the same to swing the cam into engagement with said pivoted dog to disengage the dispensing mechanism without opening said cabinet.
7. In a coin controlled vending machine including a cabinet having mechanism therein for dispensing merchandise and coupons, comprising a coupon reservoir, a coin controlled actuating member, a pivoted dog carried thereby, a shaft for operating said dispensing mechanism having a fixed dog thereon adapted to be engaged by said pivoted dog, a pivoted cam arranged to contact said pivoted dog when in one position to move the latter out of possible engagement with said fixed dog to disengage the dispensing mechanism from operation by said actuating member, a slide engaging said cam for swinging the latter, a pivoted member engaging said slide, and a lock mounted in a wall of the cabinet and connected to said member for actuating said slide.
